UNITED STATES PATENT OFFICE

2,550,621

HAIRPIN HOLDER AND OPENER

Andrew Tau, Columbia, Mo.

Application April 5, 1949, Serial No. 85,579

2 Claims. (CL 132—1)

1

This invention relates to a new and improved container and opener for hairpins.

Certain types of hairpins called bobby pins now in general use are formed of resilient metal and have the legs located adjacent each other with one leg having its free end bent slightly away from the other leg. This wedge-shaped recess at the free end of the pin is inadequate to receive even a moderately large strand of hair and the upper portions of the legs are closely adjacent each other.

The amount of opening of the free ends of the legs desired by the user varies somewhat depending on the specific use of the pin and the amount of hair to be gripped between the legs. When such pins are used during the dressing of hair, it is often necessary to hold a prepared strand of hair with one hand while picking up and applying the pin with the other hand. It is impractical to open the legs of the hairpin with one hand and the pin is often opened with the aid of the teeth. This is awkward and unsanitary and may result in damage to the teeth.

It is an object of the present invention to provide a new and improved container and opener for hairpins.

It is a further object to provide a device of this character adapted to provide means for supporting small groups of pins in substantially vertical position adjacent means for opening such pins.

It is also an object to provide such a device with the opening means located centrally and positioned above the pins in the adjacent groups.

It is an additional object to provide an opening device which operates efficiently to open the pins without lateral slippage and also with stops to limit movement of the pins in the opening operation.

It is another object to provide a device of this character which may be provided with a cover and operate as a shipping container or package for hairpins as well as a holder and opener.

It is also an object to provide a device which is simple in design and construction and adapted for commercial production by means of injection molding of plastic materials or die-casting of metals.

Other and further objects will appear as the description proceeds.

I have shown certain preferred embodiments of my invention in the accompanying drawings, in which—

Figure 1 is a side elevation of the device with its cover;

2

Figure 2 is a vertical section of the device of Figure 1;

Figure 3 is a vertical longitudinal section of the holder and hairpin opener with a pin shown in opening position; and

Figure 4 is a plan view of the holder and opener.

In the drawings, the cover is shown at 11, this cover being provided with a depending skirt 12 which abuts the shoulder 14 at the upper edge of the base flange 16 of the holder 17. The holder 17 is shown as circular in plan view and is provided with a plurality of circularly arranged cylindrical cavities 19 adapted to receive hairpins, as indicated at 21 of Figure 3. These cavities 19 are preferably formed of such cross-sectional area as to hold ten or twelve hairpins somewhat loosely spaced so that a single pin may be easily withdrawn without bringing additional pins with it.

20 The cavities 19 are also preferably of a depth dependent broadly upon the length of the pins they are designed to hold, the depth being in general approximately two-thirds to three-fourths of the length of the pins.

25 As shown in Figures 2 and 3, the body of the holder 17 is provided with a central cylindrical cavity 23 having a reduced upper portion 24 extending into the upper cylindrical flange portion 26 of the holder, the cavity being terminated by 30 the transverse portion or stop wall 27. The upper cylindrical portion 26 is of such a height as to provide an upper cavity 29 of substantial depth, this depth being of the order of approximately one-third to one-quarter of the length of the pins for which the holder is designed.

35 The upper edge 31 of the holder portion 26 is pointed or pyramidal in cross section, as shown in Figures 2 and 3. The outer face of portion 26 is provided with a plurality of vertically extending narrow ridges or lands 33 which are spaced apart a distance substantially greater than the width of the hairpins for which the holder is intended.

40 The holder with its cover may be economically manufactured and may be used as a package for shipping and sales of the bobby pins or hairpins for which it is designed. It will efficiently hold about eight dozen or a hundred pins divided between the cylindrical receptacles provided, each of the receptacles being approximately one-half inch in diameter. Due to its circular design, pins may be reached from any direction and, if properly loaded with pins, individual pins may be easily grasped and removed without disturbing other pins in the same receptacle. It has been 45 proven in practice that it is much simpler and

easier to remove a single pin from a small loose group than from a large mass of pins. The upper central cavity 29 is not designed to hold pins and is of such shallow depth that loose pins will not be retained therein.

The cover 11 is preferably formed of such size as to have a push or frictional fit with the holder so that it is held in place by friction in normal handling of the assembly. The cover may be removed and retained by the purchaser of the container and used as a cover of the container only when travelling, if it is not desired to remove and replace the cover when the pins are used.

In the use of the container and opener, a hairpin is selected from any convenient receptacle and the legs of the pin spread apart by pressing them downwardly against the pointed ridge portion 31. The ridge is circular and located centrally of the device so that it may be reached from any direction. The stop wall 27 limits downward movement of the pin so that it projects upwardly sufficiently to provide adequate leverage to spring the legs apart without undue exertion. While the thrust of the inner leg of the pin is against a point adjacent the upper edge of central portion 26, there is a lower counter thrust by the other leg against the outer face of portion 26 at a lower level. These substantially balanced thrusts, taken in connection with the central location of the portion 26 and the relatively broad base of the holder, negative any tendency to overturn the holder while opening a hairpin. It will be noted that while the leg of a hairpin inside the flange will be limited as to downward movement by the stop wall 27 the opposite leg may be slid down the outer face of the flange a substantially greater distance.

The vertical lands or ridges 33 on the outer face of the portion 26 have an important function in that they serve to guide the downward movement of the outer leg of the hairpin and prevent the pin from swinging laterally or circumferentially of the edge 31 due to the resilience of the material forming the pin. The opening of the pin, in actual practice, is usually a one-handed operation and is often performed without close visual attention to the pin. This guiding action of the ridges 33 affords efficient and uniform opening with a minimum of attention from the user.

The upper dome-shaped portion 35 of the cover

11 may have a push fit with the upper portions of the lands 33 and thus assist in holding the cover frictionally in place.

While I have shown a preferred embodiment of my invention, it is capable of variation to meet differing conditions and requirements, and I contemplate such modifications as come within the spirit and scope of the appended claims.

I claim:

- 10 1. A container and opener for hairpins comprising a body portion and a circular central flange projecting upwardly from the body portion, said flange having its upper portion sloping to a sharp edge, and a smooth, rigid, horizontal stop wall inside the circular central flange at a level substantially above the level of the body portion, and below the upper edge a distance equal to a substantial portion of the length of a hairpin with which the container and opener is adapted to be used, whereby a leg of a hairpin inside the flange will be stopped while the opposite leg may be slid down the outer face of the flange a substantially greater distance.
- 15 2. A container and opener for hairpins comprising a body portion and a circular central flange projecting upwardly from the body portion, said flange having its upper edge of substantially pyramidal cross section, and a smooth, rigid, horizontal stop wall inside the circular central flange at a level substantially above the level of the body portion, whereby a leg of a hairpin inside the flange will be stopped while the opposite leg may be slid down the outer face of the flange a substantially greater distance, and spaced vertical ridges on the outer face of the flange to guide the downward movement of said opposite leg.
- 20 30 35

ANDREW TAU.
